United States Patent Office

Des. 186,601
Patented Nov. 10, 1959

186,601

ELECTRICAL DISTRIBUTION CENTER

Robert O. Ernest, Oak Park, and Jean O. Reinecke, Chicago, Ill., assignors to Sunbeam Corporation, Chicago, Ill., a corporation of Illinois

Application September 18, 1958, Serial No. 52,680

Term of patent 14 years

(Cl. D26—13)

Fig. 1 is a front perspective view of an electrical distribution center, showing our new design;

Fig. 2 is a top plan view;

Fig. 3 is a side elevational view, the opposite side being substantially a mirror image thereof;

Fig. 4 is a cross-sectional view, taken on line 4—4 in Fig. 1; and

Fig. 5 is a cross-sectional view, taken on line 5—5 in Fig. 1.

We claim:

The ornamental design for an electrical distribution center, as shown and described.
